UNITED STATES PATENT OFFICE.

WILLIAM T. HANNA, OF CINCINNATI, OHIO.

REGULATING MEANS FOR CONVEYERS.

Application filed December 1, 1924. Serial No. 753,240.

To all whom it may concern:

Be it known that I, WILLIAM T. HANNA, a citizen of the United States of America, and a resident of Cincinnati, in the county 5 of Hamilton and State of Ohio, have invented new and useful Improvements in Regulating Means for Conveyers, of which the following is a specification.

This invention relates to improvements 10 in elevating conveyer mechanisms and is especially adapted for use with locomotive stokers wherein a pair of vertical conveyers are supplied by the single horizontal conveyer.

15 An object of my invention is to provide means whereby to regulate the relative amounts of substance conveyed by a pair of elevating screw conveyers which are fed from a common source.

20 Another object is to provide means for this purpose which will readily overcome the tendency of a horizontal screw conveyer to feed in greater quantities on the side toward which it rotates.

25 Another object is to provide means for the purpose stated which are simple of construction and operation.

Another object is to provide a means for the purpose stated which are adapted to 30 accurate adjustment.

These and other objects are attained by the means described herein and disclosed in the accompanying drawings, in which:

35 Fig. 1 is a fragmental perspective view of a stoker fuel elevating structure having embodied therein devices of my invention.

Fig. 2 is a plan view of a regulating device of my invention.

40 Fig. 3 is a side elevational view of the structure shown in Fig. 2.

Fig. 4 is a plan view of a modified form of the device of my invention.

Fig. 5 is a side elevational view of the structure shown in Fig. 4.

45 In vertical conveying mechanisms wherein two or more vertical screw conveyers are fed from a single horizontal screw conveyer the substance to be handled, for example coal, is necessarily forced in greater quantity toward the vertical conveyer which is positioned at the side toward which the horizontal screw rotates, and in consequence the vertical conveyer mentioned will receive and convey a greater quantity of fuel than one positioned on the side opposite thereto.

55 The device of my invention consists of

means mounted at the base of a vertical tubular conveyer whereby the size of the fuel receiving opening in such conveyer may be regulated. In its present embodiment 60 the device of my invention is disclosed and described as applied to fuel elevating conveyers of a locomotive stoker in which a casing 7, adapted to embrace the fire door opening of a locomotive boiler, is 65 provided with a pair of upright conveyer tubes 8 and 9, disposed on opposite sides of the fire door opening 10, and converging at their bases where they communicate with a common supply chamber 11. Conveyer 70 screws 12 are revolvably mounted within the tubes 8 and 9 and are adapted to carry fuel or the like from the chamber 11 upwardly therethrough. A horizontal conveyer tube and feed screw (not shown) are adapted to 75 move fuel or the like longitudinally into the chamber 11. The feed screw and elevating conveyer screws 12 are adapted to be rotated by any suitable means such as gears and bevel gears turning from a suitable source of 80 power. The upright conveyer tubes 8 and 9 carry flanges 13 adjacent their lower extremities and upon the side toward the chamber 11 and the walls of the tubes 8 and 9 are cut away below said flanges to 85 provide an opening 14. The opening 14 is partially closed by means of a curved plate 15, the curvature of which partakes substantially of the curvature of the walls of the tubes 8 and 9. The lower edge 16 of 90 the plate 15 is disposed at substantially the same angle as the lead of the vane 17 of the conveyer screws 12. The plate 15 partially closes the opening 14 in the end of the tubes 8 and 9 and is secured therein by means 95 of bolts 18 passing through the walls of the casings 8 and 9 and engaging in threaded perforations 19 in the grooved edges 20 of the plate 15. The grooves 20 and ribs 21 of the curved plate 15 engage complementary ribs and grooves in the edges of the walls of the tubes 8 and 9 whereby the plate is given a firm mounting upon said walls of the upright tubes. As shown in Fig. 2, a sliding plate 22 is adapted to engage the 100 inner convex face 23 of the stationary curved plate 15 with its edges 24 in engagement with suitable shouldered grooves 25 on the plate 15. The plate 15 is provided with a longitudinally disposed elongated 105 slot 26 and the plate 22 is provided with a registering threaded perforation 27. A bolt 110

28 is adapted to be passed through slot 26 and engage in the threaded bore 27 in the plate 22 and by this means the plate 22 may be adjusted longitudinally of the plate 15. The lower edge 29 of the plate 22 is disposed at a more obtuse angle than the lower edge 16 of the plate 15. In Figs. 4 and 5 is disclosed a modification of the reciprocal mounting of the plate 22 wherein the plate 22 is disposed upon the outer convex side of the plate 15 and the elongated slot 26 is carried by the sliding plate 22.

As will be noted in Figs. 1, 3, and 5 the lower edge 16 of the stationary curved plate 15 will form the upper wall of the openings 14 in the tubes 8 and 9 when the sliding plate 22 is raised to its upper limit of movement. When the plates 22 are in this position, a maximum of the upright conveyer screws 12 are exposed through the openings 14 to the fuel chamber 11. When the fuel to be fed through the conveyer comprises comparatively large pieces of coal there is experienced very little difficulty in securing an even division of incoming fuel to the upright conveyers 8 and 9 as the larger pieces of fuel will very readily ride upon the vanes 17 of the conveyer screws 12. However, when finer coal is used and especially coal wherein there is a considerable quantity of slack, such finer coal and slack will be forced in greater quantity by the horizontal feed screw from the chamber 11, either toward the right hand upright conveyer 9, or the left hand upright conveyer 8, accordingly as the horizontal feed screw revolves in a clock-wise or counter clock-wise direction. Assuming now that the horizontal feed screw (not shown) is rotating in a counter clock-wise direction and forcing fine coal into the chamber 11 from which it will be taken up by the upright conveyers 8 and 9, it has been found in practice that the left hand upright conveyer 8, having the incoming fuel originally thrust toward it, will receive a greater quantity of the incoming coal than will the conveyer 9. To overcome this inequality of supply the sliding plate 22 upon the conveyer 9 would be brought downwardly so as to bring its lower edge 29 farther down into the supply of incoming coal while the sliding plate 22 upon the upright conveyer 8 would be raised so that some of the fine coal being pushed toward the conveyer 12 therein would have an opportunity to slide downwardly off of the vane 17, before the said vane carried the coal far enough to confine it within the walls of the tube 8 and the plate 15.

It will be noted that the adjustment of the plates 22 is very simply and expeditiously accomplished by loosening the bolt 28, placing the plate 22 with its lower edge 29 at the desired height and again tightening the bolt 28. In practice, satisfactory regu-

lation of the fuel supply may be accomplished by supplying one of the devices 15 only upon the upright conveyer tube which is located upon the side toward which the horizontal feed screw is turning, however accurate regulation can be attained by providing the sliding plates upon each of the upright conveyer tubes.

What I claim is:

1. In a feed regulating device for conveyers the combination with an upright conveyer tube having a feed opening in the wall thereof and a conveyer screw extending revolubly through the tube and adapted to receive a substance to be moved, which substance passes through the feed opening in the tube, of a slidable plate mounted on the tube for adjustment over the feed opening therein, whereby the substance to be conveyed may be retained between the conveyer screw and the walls of the tube, and may be permitted to drop from the screw through the feed opening accordingly as the slidable plate is lowered and raised for decreasing and increasing the feed opening in the tube. 90

2. In a device of the class described, the combination with an elevating conveyer mechanism comprising a casing having a chamber therein, conveyer tubes having openings in their walls communicating with the chamber for receiving a substance under pressure from the chamber, an elevating conveyer screw revolubly mounted in the tube for removing the substance from the openings in the tube, of means mounted in the openings in the tubes for regulating the area of communication between the chamber and the tubes whereby the substance received by the elevating screws may be retained thereon, and be permitted to drop therefrom, according to the increase and decrease of the communication area in the tubes by the regulating means. 95

3. In a device of the class described the combination with a casing having a feed chamber therein, of a pair of upright conveyer tubes on opposite sides of the chamber and communicating therewith adjacent their lower edges, elevating screw conveyers revolubly mounted within the casings, and means for regulating communication between the chamber and the tubes. 110

4. In a device of the class described the combination with a casing having a chamber therein and adapted to receive a substance under pressure, of upright conveyer tubes communicating with the chamber adjacent the lower ends of said tubes, conveyer screws mounted in the tubes, and slidable means mounted on the lower end of each tube for regulating communication between the chamber and the tube. 115

5. In a device of the class described the combination of an upright conveyer tube having a feed opening in the wall thereof, a 130

conveyer screw rotatably mounted within the tube and having a portion thereof exposed through the feed opening in said tube, of a plate fixedly mounted upon the tube and adapted to form a partial closure for the feed opening, a movable plate mounted for slidable adjustment upon the fixed plate and adapted to be extended beyond said fixed plate for increasing and decreasing the feed opening in the tube and for covering and exposing the normally exposed portion of the conveyer screws in the tube, and means for securing the movable plate in adjusted positions.

15. 6. In a device of the class described the combination with an upright conveyer tube having a feed opening therein, of a con-

veyer screw revolvably mounted in the tube, of a plate fixedly mounted upon the tube and adapted to form a partial closure for 20 the feed opening, a movable plate mounted for slidable adjustment upon the fixed plate and adapted to be extended beyond said fixed plate for increasing and decreasing the feed opening in the tube whereby 25 the movable plate may be selectively projected beyond the fixed plate and withdrawn wholly within the body lines of said fixed plate.

In testimony whereof, I have hereunto 30 subscribed my name this 19th day of November, 1924.

WILLIAM T. HANNA.
